A technical cross-sectional drawing of a component. The drawing shows a base with a central vertical slot. A horizontal plate is positioned above the base, with a small gap between them. The base has a ribbed side. The drawing is labeled 'Fig. II.' on the left and includes numerical labels 190, 190, 190, and 198.

UNITED STATES PATENT OFFICE.

HARRY L. COMPTON, OF WASHINGTON, DISTRICT OF COLUMBIA, ASSIGNOR TO THE AMERICAN DAIRY SUPPLY COMPANY, OF BANGOR, MAINE, A CORPORATION OF MAINE.

BOTTLE-CAP MACHINE.

Application filed June 10, 1926. Serial No. 115,044.

This invention relates to machines for the manufacture of caps or closure disks formed of pulp-board or heavy paper, and designed to seal or close the mouths of bottles, jars, and the like,—more particularly bottles or jars for containing milk, cream, and similar commodities. The disk or closure is preferably, though not necessarily, of circular form, and has a recess in its upper face in which is placed and stapled, a tab which normally lies flush with the surface of the disk, but which may be lifted at one end to serve as a pull-piece by which to unseat and remove the cap or closure.

The present machine is in the nature of an improvement upon a prior machine, the improvements tending to simplification of the construction and operation of the machine, and permitting efficient production of caps of various sizes. The efficiency arises from the fact that in the present machine adjustments are possible permitting caps of different sizes to be cut from a stock strip in closely juxtaposed relation, while in prior machines the feed was constant. Therefore, when a machine capable of producing a large cap was used for production of a small cap, there was considerable wasted stock intervening between adjacent caps. The present machine is accordingly constructed on what may be termed the unit plan, there being a main frame with a plurality of driving mechanisms fixed thereon, and a plurality of special mechanisms or units also supported on the frame in operative relation with the driving mechanisms. These units are bodily removable and replaceable by identical units to permit repair, said units involving an adjustment feature of one or another character such as to permit the mechanism to function at different points in the path of the stock strip. This adjustment is necessary to allow the strip to be fed intermittently at different rates commensurate with different sizes of cap, and yet register in different points of rest with the various mechanisms which perform the successive operations necessary to production of the complete cap.

The necessary adjustment can be effected in different ways and is so effected. One way is to adjust the mechanism as a unit in

a direction parallel with the path of intermittent travel of the stock strip. This character of adjustment is used in connection with the stapler, for example. Another mode of adjustment is to mount the tool which operates on the stock strip in different positions relatively to its driving means. This type of adjustment is used in the printing mechanism in which the dies are displaced on their carrier to correspond to the desired point of action, and in the scoring and milling mechanisms. Such a construction simplifies the driving mechanism, secures the necessary range of adjustment, and permits ready replacement of worn or damaged parts.

Capability of producing economically finished disks of different sizes on the same machine, the unit construction just noted, and the relative adjustability of the various devices, hence constitute leading features of the present invention and improvements.

Other features are a novel cutter for cutting from a long strip or reel, suitable lengths of material for the formation of the tabs or pull-pieces; improved wire-cutting and staple-forming and driving mechanism, for producing and driving the staples through the tab and the disk or cap and securing the tab to the disk; special printing-form carriers and mounts, whereby the forms may be positioned for a larger or a smaller disk without disturbing or adjusting any other portion of the printing mechanism; a novel die or cutter for punching or cutting the disks from the strip or band and adaptable to larger or smaller disks; improved means for applying paraffin to both faces of the otherwise completed disks or caps; improved mechanism for delivering the disks to and feeding them into, containing tubes or cartons, and crimping said tubes or cartons to prevent escape of the disks therefrom; and means for ensuring uniform length of the filled and crimped containers or cartons. Other minor features and details of improvement will be pointed out as the description proceeds.

The invention is illustrated in the accompanying drawings, in which:

Figure 1 is a perspective view of the machine looking at its front or forward side

and designed primarily to show the parts in their relative positions, and to indicate the sequence or order in which the several operations incident to the production of a completed cap or disk are performed;

Fig. 2, a diagrammatic view illustrating the different adjustments necessary to adapt the machine to the production of complete and finished disks of two different sizes;

10 Fig. 3, a face view of a smaller disk overlying a larger one, and showing the position of the tab, which position is the same for both sizes;

Fig. 4, a face view of the completed disk;

15 Fig. 4^a, a transverse sectional view of said disk on the line 4—4 of Fig. 4, the free end of the tab being shown by dotted lines in its lifted position;

20 Fig. 5, a front elevation of the primary and secondary feed mechanism for the stock strip from which the disks are formed and cut;

25 Fig. 6, a front elevation of the mechanism for scoring or outlining the tab seat in the face of the disk, and of the milling wheel or cutter, its carrier, and the mechanism for actuating the scorer and the milling wheel;

30 Fig. 7, a cross sectional view of a portion of the main frame of the machine, showing in side elevation the parts shown in front elevation in Fig. 6;

Figs. 8 and 9, detail views of the scoring device or cutter for outlining the tab seat;

Fig. 14, a partially sectioned elevation of the staple-forming and cutting mechanism;

60 Fig. 14^a, a cross section on the line 14—14 of Fig. 14, illustrating a detail of said staple-forming mechanism;

Fig. 15, an elevation of the tab-strip feed mechanism at the rear side of the machine, showing also the mechanism whereby the 65 staple-clinching slide is elevated at proper intervals;

Fig. 16, a view of a portion of the main frame of the machine, showing in front elevation the printing mechanism, the main drive shaft, and the cam by which the printing forms are moved downward to 70 effect the printing operation;

Fig. 17, a side elevation of the printing mechanism, partly in section, the ink-roll carrying sprocket-chain being indicated in part by dotted lines;

75 Fig. 18, a bottom plan view of the pawl and ratchet mechanism for imparting step-by-step rotation to the ink-distributing disks;

Fig. 19, a top plan view of the printing 80 mechanism;

Fig. 20, a top plan view of the supporting plate for the form-carrying blocks of the printing mechanism, showing the block-holding levers mounted thereon; and the 85 post or stud of one block in position with its head partially broken away to show the gripping position of the levers;

Fig. 21, a front elevation of the same parts; the levers of the left-hand side being 90 shown in section;

Figs. 22 and 23, sectional views at right angles one to the other, illustrating the construction of and the means for adjusting, the beds or platens upon which the stock 95 strip is supported during the printing operation;

Fig. 24, a vertical section illustrating the construction, mounting and means for rotating the ink-distributing disks shown in 100 Fig. 17, the section of Fig. 24 being in a plane transverse to that of Fig. 17;

Figs. 25 and 26, front and top elevations 105 respectively of a form-carrying block for caps or disks of the smaller size, the full lines indicating the position of the attaching stud of the left-hand block and the dotted lines indicating the position of the stud of the right-hand block;

Figs. 27 and 28, front and top plan views 110 respectively of a form-carrying block for the larger sizes of caps, the right and left hand blocks being in this instance identical in construction;

Fig. 29, a front elevation of the flattening 115 or hammer device by which the staples, or the staples and tabs, are brought flush and into plane with the faces of the caps or disks, showing also the punching mechanism by which the caps are cut from the 120 stock strip and the means whereby both the hammer and punch are actuated;

Fig. 30, a partly sectional side elevation of the disk-punching or cutting mechanism, showing also the carrying band by which 125 the caps or disks are conveyed to the parafining apparatus;

Fig. 31, a top plan view of the annular or female die and of the anvil for the flattening hammer, with their supporting means, 130

showing also the means for readily attaching and removing the punching unit;

5 Fig. 32, a vertical section on the line 32—32 of Fig. 31, showing the manner of securing the hardened steel plate forming the anvil for the flattening hammer;

10 Fig. 33, a side elevation of the paraffining apparatus, and of the means whereby the caps or disks are delivered from the punch to said apparatus and from said apparatus to the packaging mechanism;

Fig. 34, a top plan view of the same mechanism;

15 Fig. 35, a transverse vertical section on the line 35—35 of Fig. 34;

20 Fig. 36, a partly sectional side elevation of the paraffining tank, showing the double-wall construction provided for the admission of steam, hot water or other heating medium;

25 Fig. 37, a face view of the receiving or socket end of the packaging mechanism.

The caps or disks are cut from a continuous stock strip of pulp-board or heavy paper, of a width slightly in excess of the diameter

30 of the intended disks, which strip is conveniently reeled and drawn forward as required by successive steps or advances of carefully measured and uniform length, and with the exception of the inking mechanism of the

35 printing unit, each unit functions during a period of rest or while the travel of the paper strip or band is arrested. To this end use is made of the Geneva stop motion, and such arrest of the stock strip and operation

40 of the various units during the periods of rest, is a characteristic of the machine, tending to perfect performance of each of the functions entering into production of the finished caps or disks.

45 The several units perform their respective operations in the following sequence as the stock strip advances:

1. The margins or walls of the seat or depression formed in the face of the disk for reception of the tab or pull-piece are produced by thin cutting blades, which cut the two longitudinal walls and one end wall to approximately one-half the depth or thickness of the pulp-board or paper employed, the other end of the recess extending to the margin of the disk. Adjustment of the point at which these cutting blades act is effected by adjusting the blades bodily on the slide which guides and actuates them.

55 2. The material included within the bounds so outlined is removed to the depth of the cut, by a rapidly rotating and travelling milling wheel. The position at which the milling wheel acts is adjusted by inserting washers or collars of different thickness on the arbor which carries said wheel.

60 3 and 4. Practically simultaneous production of a tab or pull-piece and placement thereof in the seat formed in the face of the cap, and formation and driving of a staple

through the tab or pull-piece and the disk, for attachment of the tab to the disk, concluding with a partial clinching of the staple. The device which forms the tab, positions it, and staples it, is constructed as a unit adjustable on the frame of the machine in the direction of travel of the stock strip. The actuating mechanism for these parts does not partake of the adjustment but is arranged so that it will function in any adjusted position of the unit.

5 5. Printing upon the tab face of the cap or disk, suitable legends or matter, usually indicating the dairy or source of supply of the contents of the container to which the cap or disk is to be applied. As here shown, the printing mechanism comprises two duplicate mechanisms arranged side by side, with the moving parts traveling in a direction at right angles to the travel of the pulp-board or paper strip. Adjustment of the point of action of the printing mechanism is effected by adjusting the position of the dies alone.

6 6. Hammering or pressing the partially clinched staple, to flatten the same and bring it substantially flush with the upper and lower faces of the disk or cap, and if required, flattening also any desired area of the disk itself. The hammer is of sufficient area to perform its function regardless of slight displacements of the work piece in the line of travel of the stock strip, hence no adjustment is required. This is possible because the hammer acts close to the final punching die which likewise does not require adjustment.

7 7. Punching or cutting the disk from the stock strip or band. The punching dies do not require adjustment but are similarly centered whether large or small dies be used.

8 8. Severing the slight waste portions at the advancing end of the stock strip. No adjustment is necessary at this point, since the only function of this particular mechanism is to chop up the waste and accuracy is immaterial.

9 9. Delivering the caps or disks so completed to a carrier which in turn delivers them to and between the paraffining rolls, which in turn drop the disks upon a conveyor belt which delivers them edgewise between two reversely-threaded screw conveyors by which successive disks are carried to and forced into a packing tube or carton. At the delivery end of the screw-feed conveyor device is a socket piece to receive one end of a paper tube, carton or container in which the disks or caps are packed for shipment. To prevent escape of the caps and form a stop for the foremost entering cap or disk, one end of the paper tube or container is first crimped or turned inward a short distance, usually from a quarter to a half inch, forming an annular shoulder.

within the tube, and for effecting this a rotary crimpler is located just to one side of the feeding or delivery screws.

The attendant or operator, taking a tube, 5 inserts one end thereof into the cup or rotary head of the crimpler, and slight longitudinal or inward pressure being exerted upon the tube, which is held against rotation, the curved surface uniting the bottom 10 or end wall and the side walls of the crimpler cup or head, causes the paper or pulp-board of the tube to be turned inward and laid closely against the inner surface of the tube, forming the shoulder already mentioned. 15 The tube so crimped at one end is then reversed end for end, and the uncrimped end is inserted into the socket or mouth-piece at the delivery end of the reversed screws, so that successive caps or disks, which follow in 20 quite close order, are forced into, and are carried longitudinally along, the interior of the tube until the foremost disk finds a bearing on the annular inturned end of the tube. This action continues until the caps or disks 25 completely fill the tube from the shoulder to a point usually from three-quarters of an inch to an inch from the receiving end, when the disks, being in close, compact column, reach the desired number for the tube. The 30 attendant then withdraws the tube from the socket and immediately inserts another tube, previously crimped at one end, and at once inserts the open or uncrimped end of the filled tube into the crimpler cup or head, and 35 crimps that end, so that the caps or disks filling the tube are firmly held between the annular shoulders at the two ends of the tube.

This operation is continuous during the 40 running of the machine, the caps being produced at a rate of from 250 to 300 per minute, and following in quick or close succession into the container tube or carton. It is found in practice that the attendant, after 45 a brief experience, is able to determine very accurately when a tube has received the requisite number of disks, and that any variation to one or the other side of the desired number is practically compensated 50 by like variation to the other side. It is of course a simple matter to provide a counter or an alarm which shall function after a given number of rotations of the conveyor screws, and notify the attendant that the 55 tube is filled, but this is not deemed necessary in practice.

This statement of the operations performed by the machine, and their sequence, will facilitate an understanding of the following detailed description of the various 60 units or groups of mechanism which accomplish these results.

Referring first to Fig. 1 showing the assembled machine, A indicates the framework of the machine as a whole, comprising

a horizontal bed or table 1 supported upon legs 2 at or near its ends at a height affording convenient access to the parts carried by said bed and by the upright panel 3 which rises from said bed or table. Resting on 70 the table 1 is an auxiliary or work-guiding surface made up of two portions 1^a and 1^b, spaced apart to provide room for the intervening base of the stapling unit and to afford clearance for the longitudinal adjustment of said unit. At the left with reference to Fig. 1, the auxiliary top member 1^b adjoins a base or block hereinafter described, which carries the lower die of the punching mechanism. The base of the stapling unit 80 also forms a continuation of the auxiliary table surface as later pointed out. There is thus provided what is in effect a continuous supporting bed for the work strip. Rising above panel 3 and preferably cast separately 85 therefrom and secured thereto by bolts or other fastenings, are bearings 4 in which is mounted and rotates, the main driving shaft 5 carrying at one end a belt-wheel 6 through which power from any suitable prime motor 90 is brought to the machine by a suitable driving belt or band. At the rear of the machine and parallel with the main shaft 5 is a jack shaft constructed in two sections 8, 8', which sections are axially alined and are driven in 95 the same angular direction and at the same rotative speed as shaft 5. The jack shaft 8, 8' is in effect a single shaft but is subdivided in order to permit the passage of a pitman and rock lever (see parts 90 and 91, Fig. 7). The jack shaft is carried in bearings 7, and the right-hand section 8 is driven through 100 a train of gears 9, 10 and 11 (see Figs. 1, 5, 6 and 7), the left-hand section 8' being driven by a train of gears 9', 10' and 11' (see Figs. 13, 15 and 17). The gears 10 and 10' are idlers while the gears 9, 9' are of the same diameter as the gears 11, 11'. 105

It may with advantage be mentioned here that throughout this machine, sprocket-wheels and sprocket-chains are employed to ensure positive and uniform movement of the various driven parts, since absolute timing of the machine and its various units is essential to perfect work. This result is 110 further ensured by the employment of the Geneva stop movement in connection with various of the parts, as will appear hereinafter. While, however, these two features are here stressed, it is not intended to restrict the claims specifically thereto, since it is possible to get fairly good results through the use of other connecting or transmitting and timing devices. 115

Rising from the main frame A is a post or standard 12 which carries a horizontal stud or axle 13 to receive and support a reel or drum 14 about which is wound a long strip or band 15 of pulp-board or heavy paper suitable for the production of closure 120 125 130

caps or disks. This band or strip 15 is carried through or over suitable guides as indicated in Fig. 1, to and between a pair of rolls 16, 17 carried respectively by a driven shaft 18 rotating in a fixed bearing on the main frame A, and by a movable axle 19 carried by a lever 20 pivotally supported on said frame and provided with an adjustable weight 21, which can be set to cause roll 17 to exert any desired pressure upon stock strip 15 passing between it and the companion roll 16, thus affording the requisite grip or bite of the rolls upon said strip. The rolls 16, 17 are of like diameter and are provided with intermeshing gears of like pitch, hence have equal surface motion.

As seen in Figs. 1 and 5, the shaft 18 carries a sprocket-wheel 22 turned by a sprocket-chain 23 which receives motion from a sprocket-wheel 24 carried by a horizontal shaft 25. This shaft 25 receives motion from a parallel shaft 26 through gears 27, 28 of like diameter and pitch, said shafts being carried in bearings in or upon frame A. Shaft 26 receives motion through bevel pinions 29 and 30 carried respectively by said shaft and by a vertical shaft 31 rotating in bearings on the main frame of the machine, the shaft 31 receiving rotary motion through a bevel gear 32 at its upper end, meshing with a like gear 33 carried by the jack-shaft 8. Shaft 25 has keyed or otherwise rigidly secured to it a pair of arms 34 which are spaced apart a distance sufficient to permit a Geneva stop-wheel 35 to pass between them, said arms being connected by a pin 36 which, at each revolution of shaft 25, enters one of the radial slots 37 of the Geneva stop 35, and rotates said wheel an angular distance equal to the spacing of the slots 37.

The Geneva stop-wheel 35 rotates about an axle 38 carried in a swinging carrier or support 39 pivotally mounted upon shaft 25, and slotted as at 40 to receive a clamping bolt or screw 41 by which the swinging support 39 may be held at any desired adjustment (see Fig. 5). Also mounted upon and rotatable about axle 38 is a roller 42 to which Geneva stop-wheel 35 is firmly attached, so that rotation of the stop-wheel shall impart like rotation to said roller. Above and parallel with roller 42 is a second roller 43 of like diameter, the axle 44 of which is carried by a lever 45 fulcrumed upon a bolt 46, and furnished with an adjustable weight 47 by which the upper roller 43 is urged toward its companion roller 42. Rollers 42 and 43 are provided respectively with gears 48 and 49 of like diameter and pitch, whereby the rolls are caused to turn toward each other in the directions indicated by arrows in Fig. 5, and to impart longitudinal movement to the stock strip or band 15 which passes between them.

The rolls 42, 43 and gears 48, 49 may be at any time dismounted from their axles and others of different diameter substituted therefor, so as to give a different extent of movement to stock strip 15 at each partial rotation of stop-wheel 35, and consequent partial rotation of rolls 42, 43. In making such exchange, the swinging carrier 39 in which axle 38 is supported, is freed by backing its clamping screw or bolt 41, and is swung to proper position to cause due meshing of the larger or smaller pinions 48 and 49 of the substituted rolls 42, 43.

It will be seen from the foregoing description that there is an initial feed of the stock strip 15 by the rolls 42, 43, and a secondary feed by rolls 16, 17. As the rolls 42, 43 are operated at frequent intervals through the Geneva stop-wheel 35, starting suddenly from a condition of rest, moving quickly a short distance, and as suddenly stopping, a quick pull or jerk upon the band or strip 15 is caused by feed rolls 42, 43. If this sudden pull were imparted to the stock strip at or near the drum or reel 14, it would obviously tend to unwind a considerable and undue length of the band, thus requiring constant attention thereto. It is for this reason that the feed rolls 16, 17 are employed, to hold the stock strip between them and prevent transmission of the jerk or pull to said strip at a point between said rolls and reel 14. To afford ample stock between the two pairs of rolls 16, 17 and 42, 43, the strip 15 is drawn off into a loop of considerable length between said pairs of rolls. The rolls 16, 17 are driven at a speed to draw forward a length of stock strip 15 equal to the length thereof advanced by rolls 42, 43, so that the loop between the two pairs of rolls is maintained at all times. To maintain this equal feed when rolls 42, 43, are exchanged for others of different diameter for making caps of larger or smaller size, corresponding change of rolls 16, 17 will be made.

Stock strip 15 is carried through or under suitable guides or keepers 50, one of which is shown in Fig. 17 in connection with the printing mechanism, and another in Fig. 5 just to the right of feed rolls 42, 43. As seen in Fig. 5, guide 50 is hung from or carried by lever 45, hence moves therewith and is always in position to guide the stock strip whether the feed rolls be of larger or smaller diameter. The keeper shown in Fig. 17 serves both to guide the stock strip and maintain it in proper alinement, and to prevent the lifting of said strip through the adhesion of the printing form to the band in consequence of the more or less sticky character of the ink. The several keepers also tend to hold the stock strip 15 flat and in close contact with the bed or auxiliary table 1^a, 1^b over which it travels, thus pre-

venting any buckling of said strip which might interfere with the proper spacing thereof at points to the left of feed rolls 42, 43 as viewed from the front of the machine.

The first operation following the advance of stock strip 15 by feed rolls 42, 43, to wit, that of scoring the disk or cap to outline and produce clean-cut and smooth walls for 10 the tab-receiving recess, is effected by the scoring unit B, the location of which relative to other parts of the machine is shown in Fig. 1, and the details of which are shown in Figs. 6, 8 and 9.

15 Referring now to the latter figures and primarily to Figs. 6 and 7, 51 designates a substantial bracket or casting firmly secured to the front face of panel 3 by machine screws 52 passing through the panel and 20 through bosses on the back face thereof, as seen in Fig. 7. Formed in the right-hand vertical face of bracket 51 is a vertical groove or slideway of dovetail cross section, in which is mounted and guided a vertically 25 movable slide 53 of like cross section. In practice, a wear strip is usually employed between the slide and one side wall of the dovetail slideway, pressed against the slide by screws or tap bolts 54, to ensure a close 30 fit and to compensate for wear. At its upper end the slide 53 is bored to receive the attaching end 55 of a wrist-pin 56, the body portion of which pin is eccentric to the attaching end, so that by turning said pin 35 more or less in its seat in the slide 53, the depth to which the slide shall move may be varied to determine with nicety the depth to which the scoring blades carried by said slide shall penetrate the stock strip 15. The 40 attaching end 55 and the hole which it enters in slide 53 may be threaded if desired, in which case the nut 57 will act both as a holding and as a jam nut—otherwise it will serve merely as a retaining nut.

45 58 designates a pitman, the lower end of which is bored to encircle wrist-pin 56, and the upper end of which is in the form of a divided strap or band 59 to encompass an eccentric 60, keyed or otherwise made fast 50 upon main shaft 5. At its lower end slide 53 carries two blocks 61 and 62, the upper block 61 having in its upper face a dovetail groove or slideway extending from front to rear or at a right angle to the line of travel 55 of stock strip 15, and in its lower face a like groove or slideway extending at a right angle to the upper groove or slideway, as shown in Figs. 6, 8 and 9. The groove or slideway of upper block 61 receives and fits 60 a dovetail rib on the lower end of slide 53, and the lower groove or slideway receives and fits a dovetail rib on the upper face of lower block 62, each groove being advisably furnished with the customary wear strip and 65 adjusting screws for maintaining a close

joint and preventing play or looseness. Each block is provided with an adjusting screw 63 or 64 by which to adjust it relatively to the support in which it is carried, and with a set screw 65 or 66 to clamp or hold it 70 against movement after proper adjustment. This dovetail connection is preferred because of its strength, effective guiding, and the ease of maintaining a close fit of the parts, but any other usual connection permitting 75 relative crosswise adjustment of the blocks may be employed.

As shown in Fig. 9, the block 62 has formed in its lower face two narrow parallel grooves 67, and a like third groove 68 at right angles to grooves 67, each to receive a thin V-edged blade 69 of hardened steel, the several blades being spaced as shown in said figure, to outline the seat for the tab or pull-piece in the face of the cap or disk. 85 Screws 70 passing through outer walls of block 62 bear against the several blades and hold them securely in place. The blades should closely fit the grooves to guard against lateral or facewise play.

90 During rotation of main shaft 5 and advance of stock strip 15, primarily due thereto, slide 53 is carried upward by eccentric 60, clear of said strip or band, and as the latter comes to rest the slide descends, causing blades 69 to be pressed into the face of the stock strip to a depth equal to one-half its thickness, or thereabout. The blades being thin, tempered quite hard, and brought to a keen edge, make a clean cut, producing smooth and even walls for the tab recess formed by subsequent removal of the material within the enclosing walls, to a depth equal to the penetration of the blades 69. 95 This preliminary scoring, or formation of the boundary walls, is of marked importance, facilitates removal of the material within the scored area, and obviates the production of rough or fuzzy walls, such as are caused by any attempt to remove the material without thus first sharply scoring or marking out the walls.

100 Immediately following the scoring or outlining of the tab recess, stock strip 15 is advanced by feed rolls 16, 17 and 42, 43 a distance equal to the diameter of the intended disk, plus a slight space between it and the preceding disk, sufficient to permit the cutting of each disk complete and perfect at all points and without encroachment upon a proximate disk or disks. During such advance the several unit mechanisms do not act upon, or in any manner interfere with the advance of the stock strip, though they do 115 perform some portion of their preparatory work in such feeding intervals, and effect or complete their respective functions during the periods of rest of said strip or band.

120 The stock strip or band 15 having been advanced by the feed rolls as described, that 130

portion of the band just scored by the blades 69 is brought to the second unit C, the milling wheel or cutter 71 of which effects removal of the material within the space enclosed by the scoring performed by blades 69. Unit C is seen in perspective in Fig. 1, where its relation to other units is made clear. Its construction and mode of operation are, however, better shown in the larger views, Figs. 6 and 7.

The unit C comprises an upper block or hanger 72 having a vertical slide member 73 of dovetail cross section, movable in a guideway of like cross section formed in the side face of bracket 51 opposite that in which scorer slide 53 is seated, space being provided for the usual wearing or take-up strip 74, which is held by a screw 75 against endwise movement, and is set up as required to make a close bearing by screws 76 passing through the outer wall of bracket 51, and pressing against strip 74 as indicated in Fig. 7. Rising from bracket 51 and overhanging the vertical slide member 73 of block 72 is an arm or bracket 77 in which is swiveled the cylindrical shank or body 78 of a screw 79, the threaded lower portion of which enters a tapped or threaded socket in the upper end of slide 73. The upper extremity of screw 79 is squared to receive a wrench, or is perforated or otherwise fashioned to permit it to be turned by a rod or tool. By so turning the screw, slide 73 and its attached block can be adjusted to and held at any desired height. The lower face of block 72 is provided with a horizontal slideway of dovetail cross section, as seen in end elevation in Fig. 6, to receive the dovetail rib 80 of a carriage 81 in which are journaled the shaft or arbor 82 of the milling wheel 71, and a driving shaft 83 parallel therewith, provided with a belt pulley 84, the two shafts being provided with intermeshing gear and pinion 85 and 86 to impart to the milling wheel rotation of proper direction and speed to enable it to effect quick and clean removal of the pulp or paper enclosed within the scored boundaries of the tab seat previously formed in stock strip 15. As shown in Fig. 6, the slideway in block 72 is provided with take-up or wear strip and adjusting screws, as is the case throughout the machine where such slides are shown. Further mention of this common expedient will henceforth be omitted.

As seen in Fig. 6, the carriage 81 is formed of two mating and connected sections, the walls of which are suitably spaced apart to afford room for gears 85, 86, and are formed with bearings for arbor 82 and drive shaft 83. Rotary motion is imparted by belt 87 from any convenient driving pulley to pulley 84, and by shaft 83, gear 85, pinion 86, and arbor 82 to the milling wheel or cutter 71. Carriage 81 is moved horizontally for-

ward and backward to carry the milling wheel from the inner end of the scored tab recess to the outer edge of the stock strip, to cause the necessary removal of the pulpboard or paper therefrom. This movement is effected by an eccentric 88 secured upon and rotating with main shaft 5, and encircled by the strap 89 of a three-part pitman 90 of common type, comprising two end sections and an intermediate section having its opposite ends screw-threaded respectively right and left, to enter correspondingly threaded sockets in the pitman sections. The threaded mid-section of the pitman is fashioned to receive a wrench or other tool by which to rotate it to lengthen or shorten the pitman, and the threaded portions of the end sections of the pitman are split longitudinally and formed with ears to receive transversely arranged bolts by which to tighten them upon the threaded intermediate member to prevent loosening or turning thereof after adjustment is effected. The end of pitman 90 remote from strap 89 is pivotally connected with the upper end of a lever or upright walking-beam 91, the lower end of which is similarly connected with one end of a link 92, the opposite end of which is likewise connected with a rearward extension 93 of carriage 81. Rotation of eccentric 88 through pitman 90 imparts oscillating motion to lever 91, which in turn, through link 92, imparts a reciprocating motion to carriage 81.

To prevent marring or injury of the stock strip or band 15 by the milling cutter 71 during the forward travel of said stock strip, the throw of eccentric 88 is such that the reciprocation of carriage 81 carries and holds the milling wheel forward and clear of strip 15 during the advance of said strip. The effective cutting period of wheel 71 occupies the very brief time during which the cutter is carried inward over the stock strip and again outward to clear the same, the cutting being effected on the inward movement. The relatively long belt 87 suspended from a driving pulley above the machine permits the full travel of carriage 81 and milling wheel 71 without appreciably affecting the tension of the belt, hence there will be no belt slippage. The milling cutter 71 rotates continuously. Spacing washers 71^a adjust cutter 71 laterally.

The milling operation is performed on a portion of stock strip 15 which will ultimately constitute one closure disk or cap, while the scoring is being effected on a succeeding disk-forming section of said strip. The scoring and milling of the forward disk-forming section of the stock strip having been completed, the next rotation of main shaft 5 imparting motion to feed rolls 16, 17 and 42, 43, advances the milled section to position to receive within the seat or depre-

sion so formed, a tab or pull-piece and the staple by which said tab is secured to the disk-forming section. This is accomplished by the combined units D and E (Fig. 1), 5 which like the units B and C may be removed from the machine by loosening a few fastening bolts. These two mechanisms are closely interrelated and function within the same or practically the same period of time. 10 Their construction is illustrated in Figs. 10, 10^a, 10^b, 11, 11^a, 12, 12^a, 13, 14 and 14^a.

Referring first to Fig. 10, 94 designates a drum or reel upon which is coiled a quantity of fine wire 95 sufficient for the production 15 of staples for a great number of disks or caps. The wire is led from the drum or reel through eyes or openings formed in a guiding and tensioning member 96 held at its lower end in a suitable support, and connected at its upper end to one end of a helical spring 97 which tends to draw said end outward away from reel 94, and to apply a slight tension sufficient to take up any slack that is occasioned through drawing off 20 the wire from the reel. From the tensioning member 96 the wire 95 passes between two circumferentially grooved feed-wheels 98 and 99, (see Figs. 10, 10^a, 10^b and 13) the wheel 98 being carried upon a shaft or axle 25 100, the supporting portion 100' of which has its axis parallel with but slightly eccentric to that of the portion on which wheel 98 turns. The supporting portion 100' of said axle is journaled to turn in a post bearing 101 and is provided with a radial arm 102 carrying a knob 103 slidable longitudinally through a sleeve in the outer or swinging end of said knob or handle, and having a central pin 104 which is urged by a helical 30 spring 105 toward a seat or depression 106 formed in the front edge of a plate 111 which is mounted on the table 1 and which is adjustable relatively to the auxiliary tables 1^a, 1^b, to position the stapling mechanism at the proper point in the path of the stock strip. By reason of the eccentric relation of the two sections of axle 100, a swinging movement of arm 102 will rotate the 35 journal portion of said axle about its axis, and carry the relatively eccentric wheel-bearing portion thereof and the wheel 98, toward or away from the companion wheel 99. This causes the wire lying in the grooves of wheels 98 and 99 to be firmly gripped 40 therein between said wheels. To maintain this pressure pin 104 is moved into alignment with and permitted to enter seat or depression 106. As the wheels 98 and 99 constitute the sole means for advancing wire 95, it will be seen that the feed may be started and stopped by merely swinging arm 102 to and from its locking position, pin 104 being withdrawn from seat 106 by an outward pull upon knob 103.

65 The wire-feeding wheels 98 and 99 are of

like diameter and have secured to them intermeshing pinions 107, 108, whereby they are caused to rotate toward each other on the upper or wire-receiving side, and at equal speed. Wire-feeding wheel 99 and 70 pinion 108 are made fast to a shaft or axle 109 turning in a sleeve 110 supported upon a suitable post or standard rising from the base 111 of unit D, said axle carrying at the end opposite that at which wheel 99 is 75 located, a Geneva stop-wheel 112. Intermittent rotary motion is imparted to stop-wheel 112, axle 109, feed-wheel 99 and pinion 108 by a roller 113 carried in the bifurcated end of an arm 114 mounted upon a 80 shaft 115 which receives rotary motion through bevel pinions 116, 117, carried respectively by said shaft 115 and by a shaft 118, the latter journaled in bearings at the rear of frame A. Rotary motion is imparted 85 to shaft 118 by means of a chain belt 119 passing about a sprocket-wheel 120 keyed or otherwise made fast upon said shaft and itself receiving movement from a sprocket-wheel 121 carried by the jack-shaft 8', as 90 seen in Figs. 13 and 15.

Journaled in bearings below shaft 118 is a shaft 122 carrying a combined feed roll and pinion 123 which co-acts with a companion feed roll and pinion 124, which latter 95 is carried upon a short shaft or axle 125 similar to shaft 100 in that it consists of a journal portion about which it swings or rotates in a fixed bearing, and an axle portion for the roll and pinion 124 eccentric to the journal portion. Secured to one end of shaft 125 is a lever 126 by which said shaft may be rotated in its fixed bearing to carry the portion which bears combined roll and pinion 124 toward and from combined roll 100 and pinion 123 (see Figs. 11 and 15). The lever 126 may be provided at its upper or free end with a tensioned spring 127 whereby it is drawn normally in a direction to press the rolls 123 and 124 which feed the tab strip, together to afford the requisite feeding pressure and friction on said strip. By releasing the spring the feeding of the tab strip may be instantly stopped, since the lever will then fall back and move roll 124 110 away from its companion roll 123.

Intermittent rotation is imparted to shaft 122 and consequently to roll 123, and through the gearing of the feed rolls to roll 124, by a Geneva stop-wheel 128 actuated by a roll 129 carried in a bifurcated arm 130 secured to shaft 118, said roll being carried at each successive rotation of said shaft into one of the radial slots of Geneva stop-wheel 128, and advancing said stop-wheel a distance 125 equal to the spacing of the slots. In this way the timing of the advance of tab strip 131 is accurately determined and controlled. As seen in Fig. 15, shaft 118 further carries a cam 132 which, bearing upon a vertically 130

movable slide 133 or upon an anti-friction roller 134 carried in the upper end thereof, serves to depress or to move downward slide 133, the lower end of which, or a roller 135 carried by said end, bears upon a plate 136 carried by a lever 137 fulcrumed in a hanger 138 depending from the under side of bed or table 1 of the machine frame. Plate 136 is large enough to engage the roller 135 in the various adjusted positions of plate 111. Thus although the lever 137 is mounted on the frame 1 and does not partake of the adjustment, it functions in all positions of the stapling mechanism. A helical spring 139 attached at one end to a suitable clip 140 on the guiding block 141 in which slide bar 133 is mounted and guided, and at its other end to lever 137, tends constantly to draw upward such end of the lever, and to press slide bar 133 upward and maintain its upper end or its roller 134 constantly in bearing contact with the periphery of cam 132.

The office of lever 137 is to effect a preliminary clinching of the staples formed of wire 95 fed to the staple-forming mechanism by feed-wheels 98 and 99 as above explained. As seen in Fig. 10, the wire, after passing between feed-wheels 98 and 99, enters a curved guide 142 which directs the wire by an easy curve to a grooved supporting block 143 extending through a wall of block or housing 144 through which move the staple-forming and cutting slides. Block 143 is made quite hard and projects slightly within the slide-way to support the wire while a staple length is being severed therefrom. A groove or passage of sufficient size to permit the free entrance of the wire above block 143 is formed in the wall of housing 144, as shown in Fig. 14. This opening lies in plane with the wire-supporting ledge or face 145 of an anvil block 146 movable forward and back in a guideway in a forwardly projecting extension 147 of housing or guide-block 144. The anvil block 146 is urged backward or inward by a helical spring 148 bearing at its inner end against the end wall of a longitudinal slot formed in said block, and at its opposite end against a plate 149 closing the outer end of the slideway in which said anvil block is seated. Longitudinal movement of the anvil block is limited and defined by a pin 150 passing horizontally through extension 147 and entering a slot or depression 151 formed in the upper edge or face of anvil block 146 as seen in Fig. 11. Pin or stop 150 is so located that the maximum inward movement of anvil block 146 shall bring the ledge 145 to the exact level of supporting block 143, so that the wire on entering the interior space of housing 144 shall be laid directly over and rest upon said ledge, as indicated in Fig. 14. The inner end or face of anvil block 146 is beveled or inclined as shown in Fig. 11, for a purpose 65 later pointed out.

Sliding within block or housing 144 is a compound slide consisting of a vertically slotted main member 152 of the cross section indicated in Fig. 14^a. In its lower portion this slide member 152 is transversely and forwardly slotted, and within this cross slotted portion and on either side of the forward slot, are inserted hardened steel plates 153 which are secured in place by rivets passing through the front and rear walls of slide member 152. These plates 153 are slightly narrower than the forward slot, and have their inner vertical edges longitudinally slotted to receive the longitudinal edges of a thin steel plate 154 carried in the transversely slotted lower end of a second slide bar or member 155. This slide member fills the space between plates 153 and the forward slot, and is guided in and by such forward slot. Slide member 155 is lower than slide member 152, and its upper end rises above said slide 152 and terminates in a T-head, as shown in Fig. 14. The plate 154 is somewhat wider than the slide member 155, and its edges project past the sides thereof and enter grooves formed in the plates 153 and in the inner walls of the slot formed in the face of slide member 152, said walls being longitudinally grooved or slotted to receive the protruding edges of plate 154. The front portion of both slide members 152 and 155 is broken away in Fig. 14 at the lower ends thereof, to expose the plates 153 and 154 to view. The forward face of slide member 155 is beveled at its lower end as shown in Fig. 11, and serves, when said slide member is forced down to its full depth, to force back anvil block 146 against the pressure of spring 148 which, however, moves said block inward to the point permitted by pin or stop 150 when slide member 155 again rises.

Above block or housing 144 is a larger housing 156 which is firmly secured to the front face of panel 3, and is bored to form three vertical spring sockets, the middle one of which is seen in Fig. 11 in section. Within each of the spring sockets is inserted a strong helical spring which, when free from compression, protrudes some distance above housing 156 and bears beneath a head, such as 158, of a rod or stem, as 159. Head 158 is in this instance attached to a slide bar 160 guided in a slideway forward of the spring socket, in which guideway it is held by a 110 cover-plate 161 common to the middle slideway and to other and similar slideways formed one on either side of that which receives slide 160. Stem 159, extending downward from head 158, enters and nearly 115 fills the interior of spring 157, which is maintained in vertical position by said rod or stem and caused, when subjected to pres-

sure, to collapse, fold upon fold, without tendency to buckle or bend laterally. Secured to the lower end of slide 160 is a box-like block or casting 162 having a removable front cover-plate 163, and within block 162 is a rectangular space to receive a yoke or slotted coupling member 164, the upper end of which is cupped to receive a helical spring 165. The cupped upper portion of coupling member 164 is somewhat shorter vertically than the interior space in block 162, and the spring 165 is of such length that it projects above the cup, presses against the top wall of the space within block 162, and requires to be placed under some compression in order to permit the proper seating of the cup within the box or interior space of block 162. The portion of coupling member 164 immediately below the cup is reduced in cross section to form shoulders which rest upon inwardly projecting ledges surrounding the opening in its bottom through which the reduced portion of said member 164 passes. By this construction coupling member 164 is afforded a slight vertical movement relative to block 162, but under normal conditions the cup will be seated upon the ledges of the containing box by gravity and pressed thereto by the expanding force of the compressed spring 165.

A short distance below block 162 the coupling member 164 is enlarged and provided with a T slot extending from front to rear, of dimensions to receive the T-head of slide member 155. This connection between the upper slide 160 and the lower slide member 155 causes the two to move in unison, but permits a slight downward movement of the upper slide independently of lower slide member 155, if the movement of the latter be obstructed by any considerable resistance. Slide 160 carries at its upper extremity a roller 166 which, through the tendency of spring 157 to expand, is forced upward by the pressure of the spring beneath head 158, which as before mentioned is attached to slide 160. This upward pressure causes the periphery of roller 166 to bear against the circumferential surface of a cam 167 secured to and rotating with main shaft 5, as seen in Fig. 10. As cam 167 rotates, the slide 160, and consequently slide member 155, will be forced downward a distance equal to the throw or swing of said cam, or sufficient to carry the lower end of slide member 155 downward to the incoming tab strip 131, seen in Fig. 11, in which descent the beveled front face of slide member 155 forces back anvil block 146 as before explained. Slide member 152 is secured to a horizontal cross bar 168 extending from one to the other of two slides 169 and 170 moving in guideways formed in block or housing 156 on opposite sides of the slideway which receives slide bar 160, as shown in Fig. 10.

The cross bar 169 is set into a transverse recess in the back wall or face of slide member 152, and into corresponding recesses in the lower ends of slides 169, 170, the parts being firmly connected by bolts or screws. 70 Similarly, the upper ends of slides 169, 170 are connected by a cross plate 171, seen in Figs. 10, 11 and 13. The slides 169, 170 thus connected at top and bottom, constitute a rigid rectangular frame, and each slide 169, 170 is provided at its top with a roller 166, a block or head 158, and a depending rod or stem 159 carried by such head and entering an upright helical spring 157 seated in a socket in block or housing 156, in all respects the same as in the case of slide 160 shown in Fig. 11. The rollers 166 of slides 169, 170 bear against the peripheries of two cams 172 and 173 secured to and turning with main shaft 5, so that upon rotation of the shaft said cams force down the rectangular frame, carrying down simultaneously and equally the two slides 169, 170, and consequently cross bar 168, and exerting a strong and powerful pressure to move downward slide member 152 carried by said frame. The cross connections between slides 169, 170 give such rigidity to the frame that in the event of failure of breakage of either cam 172 or 173, or of either of the co-acting rollers 166, the frame would still be carried down and the slide member 152 would be properly operated. 90 The cams 167, 172 and 173 are so plotted or developed as to cause simultaneous but unequal movements of slides 152 and 155, the function of which slides is to cut a staple length from the wire 95, to form the staple, and finally to drive it through the tab strip 131, which is cut and simultaneously positioned beneath said slides. The operation of producing the staple will be readily understood upon referring to Fig. 14, in which the wire 95 is shown lying upon block 143 and across the ledge or supporting face 145 of anvil block 146. Slide member 155 moves down under the influence of the cam until it bears upon the wire lying down ledge 145, then comes to rest under an eccentric portion of cam 167 at that time bearing upon roller 166, while cams 172 and 173 force down slide member 152 causing plates 153 to pass the end of wire-supporting block 146 and to shear the wire in passing, the two plates being carried downward on opposite sides of anvil 146 and bending downward on opposite sides thereof those portions of the wire between the anvil and the walls of the slideway in which slide 152 moves. 110 After the staple is thus formed, the beveled front face of the lower end of slide member 155, bearing against the beveled front of anvil block 146, forces the same back from under the formed staple and carries the staple downward before it, guided until the points 115 120 125 130 135 140 145 150 155 160 165 170 175 180 185 190 195 200 205 210 215 220 225 230 235 240 245 250 255 260 265 270 275 280 285 290 295 300 305 of the staple reach or pass through the positioned tab or pull-piece and the cap or disk, by the plates 153. When the drive is completed, rotation of the cams brings over 5 the respective rollers 166 their portions of shorter radius, permitting the slides under the pressure of springs 157, to rise to their uppermost positions.

At this point the manner of feeding in 10 and guiding the tab strip 131 to produce the tabs or pull-pieces and positioning the same over the disks, may with advantage be explained. At the rear of bed or table 1 is a pair of feeding rollers 123, 124, previously referred to and described as to their mounting and mode of driving. Between 15 said feeding rolls is led a narrow strip 131 of tough, strong paper, preferably red rope manila, though other paper or material may 20 be used. The width of strip 131 is that required for the finished tab or pull-piece, and such as will fit within the seat or recess cut by the scoring blades 69 and milling cutter 71. Strip 131 is drawn from a long coil 25 carried by a drum 174 journaled in a support 175 projecting from the back of panel 3, and guided in its passage by a deeply flanged pulley 176. The feed rolls 123, 124 are 30 geared to rotate toward each other at the bite of the rolls, and are caused to exert the requisite pressure by the pull of spring 127 attached at one end to lever 126 and at the other end to the frame A, as seen in Fig. 35 11. A stop-screw 177 limits the inward movement of lever 126 and the consequent approach of rolls 123, 124, hence the pressure exerted thereby. Strip 131 is carried 40 through a passageway or between upper and lower plates, and through a removable slide 178, shown detached in Fig. 11^a, which slide lies just in rear of compound stapling slides 152-155.

Pivoted at its upper end to a supporting post 179 is a swinging arm or carrier 180, the lower end of which is cross slotted and longitudinally bored to receive a sliding block 181 and above it a helical spring 182 which, being placed under compression between the top of the bored seat or socket and the upper end of block 181, tends to force said block outward. The outward movement of block 181 is, however, restricted by a pin 183 which passes through said block, and has its ends projecting into holes or openings 50 184 in the side walls of carrier 180. Block 181 is itself slotted in the direction of travel of stock strip 15, to receive a circular cutting wheel 185 carried upon a pin or axle 186 passing through carrier 180. This cutter is preferably made of tool steel, quite thin, brought to a sharp V edge, and tempered quite hard. It is carried back and forth over a co-operating bed or plate 187, also advisably made of tempered steel. The 55 movement of block 181 is effected by an eccentric 181^a and eccentric rod 181^b, the eccentric rod being pivoted to a threaded rod 181^c which is adjustably connected with the swinging carrier 180, as best shown in Figs. 10, 10^a, 10^b, 11 and 13. The parts are so 60 dimensioned and arranged as to maintain the periphery or cutting edge of wheel 185 constantly in bearing contact with plate 187 during and notwithstanding the swinging of carrier 180 about the pivot at its upper 65 end. The travel of cutter 185 during the oscillation of carrier 180 carries it directly across the path of tab strip 131 which, if in position, is severed by said cutter at each swing outward and back, the double passage 70 tending to ensure complete severance of the tabs.

In Fig. 11 tab strip 131, or a tab cut therefrom, is shown projecting into the space beneath the inner end of anvil block 146 and also beneath the compound stapling slide 152-155, and directly over stock strip 15, which at this point lies upon base 111 of the stapling unit. The space between the leading end of tab strip 131 and cutter 185 75 is, as here shown, equal to the length of three tabs, and it will be seen upon referring to Fig. 11, that three such tabs are positioned between cutter 185 and the forward end of the leading tab α . The feeding mechanism of the machine is such, and is so adjusted for a given diameter of cap, that the portion of stock strip 15 which is to constitute a cap or sealing disk will be brought 80 beneath stapling slides 152-155, with its 85 tab seat directly in alignment with the tab strip, so that the leading severed tab will fall into said seat. The timing of the parts by the described gearing and Geneva stop devices is such that just as the leading tab α reaches the point indicated and falls into 90 its seat, slide member 155 descends and drives the staple through the tab and the stock strip, the anvil block 146 being forced 95 back out of the path of slide member 155 by the beveled front face of the latter in its descent, as before explained.

It occasionally, though rarely happens that tab strip 131 contains imperfect portions, or that from one cause or another a 100 severed tab or a fragment of the tab strip, will become jammed in the passage provided for it between cutter-wheel 185 and the place at which the leading tab is discharged; or that two or more tabs or fragments of 105 tabs will be delivered beneath the stapling slides 152-155. Such accumulation limits the possible descent of stapling slide 155, and were no provision made to avoid such consequence, or if in other words, said 110 slides were forced down without any provision for yielding at a point between the lower end of slide 155 and the cam 167 by which it is operated, there would be great 115 danger of breaking some of the machine. It 120

is for this reason that yielding connections 162, 163, 164, 165 are provided. Obviously, the same is true of slide 152, and for this reason an analogous yielding connection is 5 provided in the slide bars 169, 170 as shown in connection with slide 169, Fig. 10, where parts are broken away for this purpose. Any connection which will permit a relative sliding or telescoping action of upper and lower 10 sections of the slides, with a spring tending to force them longitudinally apart, will serve the purpose. That shown in connection with slide 169, and which will of course be duplicated in slide 170, is analogous to the connection between swinging carrier 180 and block 181, Figs. 12 and 12^a.

In the event that tabs, or portions of tab strip 131, should jam in the passageway provided for the tabs α between cutting 20 wheel 185 and the stapling point, it would be difficult to remove the obstruction between those points were not special provision made therefor. This, however, is done by providing the slide 178, which is movable 25 across the path of tab strip 131, and capable of being withdrawn at one side thereof. As shown in Figs. 11 and 11^a, this slide has a V rib on its upper surface to fit a corresponding slideway in the lower side of block or 30 housing 144, by which it is accurately guided and held in place, and to prevent its accidental displacement there is provided on the outside of block 144 a spring 188 which presses against the outer end of the slide 35 and holds it to its seat, as shown in Fig. 10. The spring can be swung to one side when it is desired to withdraw slide 178. A passageway 189 is formed through slide 178 at a right angle to the direction of its insertion and removal, or in the direction of travel 40 of tab strip 131, and there will be held in said passage the several tabs α severed by cutter-wheel 185. These and any particles within passageway 189 will be withdrawn 45 with slide 178 and can then be readily removed, after which the slide is replaced and the work of the machine will proceed. The leading tab α as it passes out of passageway 189 of slide 178 should be guided to maintain 50 it in perfect alinement with the tab seat in the cap or disk above which it is discharged. To this end slide 178 is provided with projecting guides 190 of the form shown in Fig. 11^a.

55 Immediately after the placing of tab α in its seat or recess in the stock strip 15, the advancing staple driven by slide member 155 passes through the tab and the cap or disk to be formed from the stock strip, and 60 as its ends pass downward they are bent inward toward each other by the mechanism illustrated in Fig. 14. This comprises a pair of clinching jaws 191 of substantially diamond shape, mounted upon horizontal pivots 65 192 in a slot 193 formed in the base member

of unit D—E, and normally standing as seen in Fig. 14, with one long edge face of each jaw resting on the bottom of slot 193, and another long edge face thereof lying horizontally beneath stock strip 15, while a third 70 pair of edge faces incline downward toward each other in position to deflect the descending legs of the staple inward toward each other. The outer end of the clinching jaw 191 overhangs the upper end of one or the 75 other of two vertical rods or stems 194, which rise through bed or table 1 and into slot 193. Said stems are each provided with a fixed collar 195, beneath which bears the upper end of a helical spring 196 encompassing the 80 stem and resting upon a supporting plate 197 spaced away from the lower face of bed 1 by spacing sleeves 198, and drawn and held firmly against the sleeves by screws or bolts 199 screwed into the lower face of said bed. 85 One such sleeve and bolt can be seen in Fig. 10, and another such sleeve may be seen in Fig. 14. The stems 194 pass downward through holes in plate 197 and are thus guided and maintained in true vertical position. 90

Rising through plate 197 and through bed or table 1 of the machine and through the bottom of slot 193, is a rod 200 the rounded upper end of which bears beneath the inner or proximate ends of the clinching jaws 191, the descent of said rod being restricted by a stop-collar 201. When the legs of the staple are driven through the tab and stock strip, they encounter and are deflected toward each other by the inclined faces of jaws 191 in their path. As such inward deflection begins the rod 200 rises, rocking jaws 191 upon their pivots and bending or folding the staple legs upward into contact with the 100 under face of stock strip 15, or into the form shown in said band in Fig. 14. During the rocking of clinching jaws 191 their outer ends bear upon and press down the outer ends of the clinching levers, thereby compressing springs 196 and storing up force which on descent of rod 200 restores the clinching jaws to their normal position, in which they are represented in Fig. 14. Beneath and in contact with the lower end of rod 200 is arranged a flat plate or disk 202 carried at one end of lever 137, best shown in Fig. 15, and previously described as fulcrumed in a hanger 138 beneath bed or table 1. As shown in said Fig. 15, the rear end of lever 137, which reaches to the rear of the machine, is drawn upward by a spring 139, causing its forward end and plate or disk 202 carried thereby to be drawn down, thus 110 permitting rod 200 to fall to its normal position as indicated in Fig. 14. To elevate rod 200 at the proper time to effect the bending or initial clinching of the staples, there is provided the vertically movable slide bar 133 and actuating or depressing cam previously 115 described. The setting of said cam brings it into action at the precise moment at which the inwardly bending staple legs require the clinching effect of jaws 191.

5 The clinching completed, stock strip 15 is again advanced through the action of feed rolls 42, 43, carrying the tabbed section of said stock strip to the first half or division of the double printing mechanism, which as 10 a whole constitutes unit F. This is shown in its proper relation to the other units in Fig. 1, and in detail in Figs. 16 to 28 inclusive.

Referring first to Fig. 16 there will be 15 seen a vertically reciprocable slide 203 movable in a slideway on the front face of panel 3 of main frame A, and carrying at its lower end the printing forms 204 which are preferably electrotypes, though stereotypes or 20 other suitable forms may be used. Slide 203 is provided at its top with a roller 205, the periphery of which bears against the circumferential face of a cam 206 secured upon and rotatable with main shaft 5, and said slide 25 is pressed upward by a helical spring 207 seated in a recess in the front face of panel 3, as indicated in Fig. 16. The lower end of said spring rests upon the lower wall of said recess, and its upper end bears beneath a 30 lug or shoulder on the back of slide 203. Spring 207 is advisably introduced under slight compression with the slide at its highest elevation, so that the spring will be further compressed as cam 206 rotates, and hence will promptly and certainly raise slide 35 203 as the cam turns and its portion of smaller radius bears upon roller 205.

Extending outward from the front and rear of bed 1 and its support are brackets 40 208 and 209 in which are journaled shafts 210 and 211 (see Figs. 17 and 19), carrying at their ends sprocket-wheels 212 and 213 about which pass endless sprocket-chains 214. Shaft 210 rotates in fixed bearings in 45 brackets 208. Shaft 211 rotates in boxes 215 slidable in ways in brackets 209 and urged outward by springs 216, indicated by dotted lines in Fig. 17, the springs tending to maintain a proper degree of tension or 50 tautness of chains 214, while allowing a slight approach of shaft 211 and sprockets 213 toward shaft 210 and sprockets 212. Chains 214 carry on their inner or proximate faces, blocks 217 in which are formed 55 bearings for cross shafts 218 carrying inking-rolls 219, two such rolls being shown on each cross shaft in Figs. 16 and 19. The main body 219 of each inking-roll may be made of or covered with ink-roll composition, or otherwise surfaced to carry and deliver to the forms 204 a proper film or coating of printing ink. The outer extremities 60 of said rolls are, however, formed into or provided with bearing rollers 220, slightly

larger in diameter than the body portions 65 219, and designed to roll upon tracks 221 depending from the lower face of form-carrying head 222 carried by the lower end of slide 203, as best seen in Fig. 16. By this arrangement the rollers 220 are accurately 70 guided in their travel beneath printing-forms 204, and the inking-rolls 219 are permitted to bear upon said forms with just the force or pressure suitable to proper deposit of ink thereon. The rolling contact of 75 rollers 220 with tracks 221 imparts rotation to inking-rolls 219, and causes the ink to be applied to forms 204 by a rolling contact which prevents any tendency to smear the ink or cause uneven application thereof. 80 The cross shafts 218 and their bearing blocks 217 are preferably arranged in pairs, as indicated in Figs. 17 and 19, and each cross shaft carries two separate rolls comprising each the body portion 219 and the roller end 85 220.

Beneath bed or table 1 and below the lower stretch of chains 214 is arranged a series of ink-distributing disks 223, shown in top plan view in Fig. 19, and indicated 90 by dotted lines in Fig. 17 and in enlarged sectional view in Fig. 24. These disks are rotated during the passage of the ink-rolls over their upper faces, through the mechanism illustrated in Figs. 17 and 18. As 95 shown in Figs. 17 and 24, each disk 223 is carried at the upper end of a shaft or arbor 224 rotating in a vertical bearing formed in a block or housing 1, said bearing preferably having a lining 225 of Babbitt or other 100 anti-friction material. Secured upon the lower end of each arbor 224 is a ratchet wheel 226, and lying between the two parallel groups is a bar 227 carrying three pairs of spring-pressed pawls 228 (see Fig. 18), 105 to engage with and impart step-by-step rotation to ratchet wheels 226 as bar 227 is reciprocated longitudinally in supporting guides 229. As here shown, two pairs of 110 pawls 228 are pointed in one direction to engage their ratchet teeth on the movement of bar 227 in one direction, and the intermediate pair of pawls are pointed in the opposite direction and act on the return movement of said bar. 115

Slide bar 227 is reciprocated through the action of a radial arm 230 carried by a shaft 231, and rocked by a second radial arm 232 carrying at its free end a roll 233 which bears against the periphery of a cam 234 secured upon shaft 211, the lower arm 230 being connected with slide bar 227 by a bar 235. The upper arm 232 is drawn toward 120 cam 234 and held in contact therewith by a spring 236, and affords the necessary force 125 to effect the movement of slide bar 227 in the direction opposite that in which it is moved by the throw of cam 234. By thus

reversing the direction of rotation of distributing disks 223 a very thorough and even spreading of the ink is effected.

At the outer ends of brackets 208 are located ink fountains 237 provided at their inner sides with ink-delivery rolls 238 carried upon a shaft 239 journaled in bearings in said brackets, and having at one end a sprocket-wheel 240 which receives rotary motion through a sprocket-chain 241 driven by a sprocket pinion 242 on the end of shaft 210, said shaft receiving its motion through the chains 214 and their sprockets 212, 213. Shaft 211 is rotated by an endless chain 243 passing about a sprocket-wheel 244 carried by jack-shaft 8', and passing about a companion sprocket-wheel 245 on the end of shaft 211. Under the construction thus described, chains 214 travel in the direction indicated by arrow in Figs. 17 and 19, and as inking-rolls 219 are carried about shafts 210 their circumferential faces come into contact with ink-delivery rolls 238, the rolls 219 being more or less rotated about their axes through the contact with the upwardly moving face of said ink-delivery rolls. After passing said ink-delivery rolls, the rolls 219 pass over the top face of the block or form in which ink-distributing disks 223 are mounted, the disks being flush with the top face of said block, and the rolls 219 passing over said face of the block and over the distributing disks 223. As the rolls 219 are rotated by the frictional contact with the ink-covered surfaces, and as the distributing disks successively passed by rolls 219 rotate alternately in reverse directions, a very complete and thorough distribution of the ink over rolls 219 is effected.

From the distributing disks 223 rolls 219 are carried upward around sprocket-wheels 213 and beneath printing forms 204 carried by slide 203, which slide at the time of arrival of rolls 219 is at its uppermost position. Rolls 219 travelling beneath forms 204 and in contact therewith, and rotated by the end rollers 220, as above explained, delivered to said forms an even and adequate supply of ink, and pass on toward the ink-delivery fountains and rolls to receive a fresh supply for the next printing operation.

By employing several sets of rolls 219-220, each set is brought to the form-inking position on a partial travel of chains 214 through their complete range or circuit. The dimensions of the sprocket-wheels and the spacing of rolls 219-220 are carefully calculated so that one set of rolls will pass beneath and ink the forms on each rotation of main shaft 5 and each advance of stock strip 15. As shown, two rolls 219-220 are carried by each cross shaft 218, and two printing-forms 204, respectively in alignment with the two rolls of each cross shaft,

are carried by slide 203. These parts are spaced to correspond with the advance of stock strip 15 at each single step, but as the length of such step or advance will be varied as larger or smaller caps or disks are to be produced and printed, the inking-rolls are made of sufficient length to apply ink to forms 204 suitable, and properly spaced apart for, one or another size of cap or disk. The manner of mounting the forms 204 and securing proper positioning or spacing thereof will presently be explained in connection with Figs. 20 to 28 inclusive.

As shown in Fig. 16, the form-carrying head 222 is of a measurement permitting it to descend between the chains 214 to bring forms 204 into contact with stock strip 15 lying upon bed 1 and held down by the keepers 50 slightly overlapping its longitudinal edges, as seen in Fig. 17. At each rotation of main shaft 5, cam 206 forces down slide 203 and produces an impression from each of printing forms 204 on stock strip 15 beneath the same, if the forward end of said strip has reached the second line of forms; otherwise only one impression is made upon strip 15. This latter condition, however, will obtain only on the first passage of the leading end of stock strip 15 through the machine. If the leading end has reached the second form 204, two impressions will be made upon said strip, spaced apart the proper distance to permit each to appear upon a separate cap or sealing disk ultimately to be cut from the stock strip. In practice, the printing is preferably arranged in concentric circles, and the first impression is encircled by the second, or vice versa. It is usual to print the different forms in inks of different color. Obviously, more than two colors may be used in the printing without in any manner interfering one with another, by providing a greater number of inking-rolls, printing forms, distributing disks, and the like, and lengthening the machine accordingly, but two colors are usually deemed sufficient.

It should be noted here that, as seen in Fig. 16, the form-carrying head 222 is constructed with two horizontal portions one above the other, leaving space between them sufficient for the attaching necks or studs of the form-holding blocks 246 and their holding clamps 247.

The manner of mounting the printing forms 204, retaining them in place, and varying their relative positions, will now be explained. Fig. 20 is a top plan view of the lower horizontal portion of form-carrying head 222 which, as shown in Fig. 21, is secured to the upper portion of said head by bolts. The lower portion or member of head 222 is provided with two circular openings 248, 249, carefully drilled or bored to receive the cylindrical studs 250 of the form-

carrying blocks 246. Studs 250 are circumferentially grooved near their upper extremities, producing a reduced neck 251 overhung by a head 252. The floor of the 5 lower member or head 222 of slide 203 is slightly raised around the openings 248, 249 and thence to the front of the floor or support, to form seats 248^a, 249^a for the stud-locking clamps 247. These clamps consist 10 of each of two flat levers fulcrumed on the raised seats, and having diverging ends extending outward beyond the front edge of the floor or support, the portions extending backward from the fulcrum screws having 15 their opposing edges cut out to form semi-circular seats for the necks 251 of studs 250. The inner ends of the levers are connected by tension springs 253 by which they are caused normally to move toward and engage 20 the necks of the studs, and to lie beneath the heads thereof, thus preventing any downward movement of the studs and their blocks 246. The blocks are applied by passing studs 250 upward through the openings 25 248, 249, the rounded heads of said studs forcing apart the inner ends of levers 247^a, 247^b, and said levers being separated by drawing together their diverging outer ends. When the studs are passed entirely through 30 the openings, and blocks 246 are brought snugly against the under face of the perforated plate, the levers are released, and engage beneath heads 252 of studs 250, as shown in Fig. 21. The form-carrying blocks 35 may hence be quickly removed and replaced whenever necessary.

Each block 246 has a dovetailed slideway in its lower face, the walls of which extend in a direction at right angles to the length 40 of the machine or the travel of stock strip 15. The printing-form 204, electrotype or other, is fashoined to fit the dovetailed slideway, its printing face projecting slightly below the same, as indicated by dotted lines in 45 Figs. 21, 25 and 27. In order to space the printing-forms of the two series at a distance apart suitable to the printing of larger or of smaller caps or disks, the studs 250 are positioned at different distances from 50 the center of blocks 246, toward one or the other side thereof, as indicated by dotted lines in Figs. 25 and 26. As the openings 248, 249 which receive the studs 250 are formed at a fixed and unchangeable distance 55 apart, it follows that if said studs be differently placed upon blocks 246, that is, nearer or less near to a given side, the block itself will project further or less far in the opposite direction. By having two series 60 of blocks 246 with studs 250 thus differently positioned, and merely exchanging said blocks, the printing mechanism may be at once adapted to the printing of either size of cap or disk. Further variations in placement of the studs would permit printing in 65

proper position upon a greater number of sizes of disks.

It is sometimes difficult in making and assembling the parts of the printing mechanism, to get perfect parallelism between the 70 printing forms and the bed over which stock strip 15 lies during the printing operation. It is also desirable to compensate for slight variations in the thickness or depth of printing forms. To this end there is provided 75 directly beneath each printing-form 204, an adjustable bed member 254 which may be of any suitable outline, but preferably circular. This member 254 is fitted accurately within 80 a seat of like contour formed in bed plate 1 of the machine frame, and has beneath it a wedge member 255 which fits a mating groove in the lower face of bed member 254 (see Figs. 22 and 23). By adjustment of wedge 255 in a direction transverse to the 85 member 254, the latter is raised or lowered as required. To effect such adjustment wedge member 255 is provided with an arm or bar 256, notched at its outer extremity to receive the circular flange 257 of a screw 90 258 threaded into a hole tapped in the bed 1, as shown in Fig. 23. Rotation of screw 258 causes it to move lengthwise, and to carry with it bar 256 and wedge member 255. This wedge member is preferably made of a 95 width equal to the diameter of bed portion 254, so as to afford broad and ample support for said bed portion.

Fig. 2 shows diagrammatically the manner of adjusting the several units which act 100 upon stock strip 15 to produce the ultimate caps or seals, dotted lines indicating the extent to which and the directions in which different units are adjusted to compensate for the difference in size of the different caps or disks produced by the machine. It will be observed that the last disks of the two rows center at the same points, and that there are more disks in one series than in the other. 105

After the printing has been effected by the first and second forms, if two be provided, stock strip 15 is advanced to bring the section constituting the particular cap or disk under consideration, to unit G, the final clinching and flattening device. As seen in 110 Fig. 29, this comprises a simple, vertically movable slide or plunger 259, moving in a slideway formed in a block or casting 260 secured in any convenient way to the front of panel 3. Slide or plunger 259 has its 115 lower end slotted in the direction of travel of strip 15, to receive a hardened steel plate 261 to co-act with a like plate 262 set in a seat in a block 263 set into the auxiliary table member 1^b. The two plates 261, 262 are positioned to register one with the other, the upper one to form a hammer to strike or press upon the top or closed end of the applied staple, and the lower plate serving 120 as an anvil to support the staple, so that it 125

and the tab secured by it may be flattened down flush with the upper face of stock strip 15, and that the legs of the staple may be similarly brought flush with the lower face 5 of said strip. The wire employed for making these staples is flat and quite thin, and this compression can be safely made without fear of breaking or cutting through the stock strip or the tab. This flattening is important 10 where the caps are to be introduced into magazines and fed therefrom to filled bottles or jars, since being flush and smooth on both faces, the caps or seals will stack properly, will slide one upon another, and may be 15 fed out by the usual feed slide, which is of the same thickness as the cap or seal, or approximately so.

The plates 261, 262 are secured in place by set screws, as shown in Figs. 29 and 32. 20 Slide or plunger 259 is vertically reciprocated by means of a pitman 264, the strap at the upper end of which encompasses an eccentric 265 carried by main shaft 5. The lower end of hammer slide 259 may be made 25 of size to cover any desired portion, or the entire area, of the cap or seal, and thus caused to flatten and bring into plane the whole disk. This, however, is not deemed necessary ordinarily. The plunger head is 30 made large enough to operate effectively regardless of the size of disk, and no adjustment of its position is necessary.

The final unit of the series, unit H, is the 35 punching or cutting out die which cuts or punches the completely formed disk, cap or seal from stock strip 15. This comprises a vertically moving slide 266 guided in a slide-way formed in the same block or casting 260 in which clinching slide 259 is carried (see 40 Fig. 29). Slide 266 is raised and lowered by a three-part pitman 267 comprising two main portions connected by a right and left threaded intermediate portion, the end portions being provided with clamping devices 45 to prevent accidental turning of the intermediate portion. This is a common device but quite important in the particular situation indicated. The strap at the upper end of pitman 267 encompasses an eccentric 268 carried by main shaft 5, rotation of 50 which reciprocates slide 266 and the parts carried thereby.

At the lower end of slide 266 there is a 55 substantial head or block 269, having at its corners vertically bored bushings 270 which encircle vertical guide rods 271 securely mounted and anchored in the lower die carrier block 274 which alines with and is contiguous to the auxiliary table 1^b. The block 60 274 is removably attached to table 1. The purpose of rods 271 is to give the utmost stability and accuracy of movement to the die 272 carried beneath said block 269 (see Fig. 30), and to cause it to register with an 65 annular female die 273 mounted upon the

block 274. The lower end of slide 266 is enlarged above plate 269, and the two are bored and later filled by a cylindrical plug 275 flanged at its lower end as shown in Fig. 30. The purpose of thus boring these parts 70 is to get a central point from which to measure and locate, or by which to position, the die members, both to ensure the registering of said members under normal conditions and to enable them to be adjusted 75 for units of different size.

Lying immediately beneath block 269 is a plate 276 slotted in a direction transverse to the travel of stock strip 15, to receive clamping or fastening bolts 277 passing 80 through block 269. Upon loosening said bolts the plate 276 and the parts carried thereby may be moved toward or away from the upstanding panel 3 of the main frame. Plate 276 is centrally drilled and tapped to 85 receive a screw 278 which, passing centrally through the male die 272, secures the latter to said plate so that it shall partake of the adjustments of plate 276. The female die 273, which is of annular form and has a 90 shearing edge to closely encircle the circumferential cutting edge of male die 272, is seated upon a shouldered plate or slide 273^a having slots extending toward and from panel 3 of the main frame in the same manner as the slots of plate 276, to receive 95 clamping bolts 274^a by which said plate 273^a is made fast at any suitable adjustment to its supporting or base block 274.

The outer edge of stock strip 15 maintains 100 always a given position or distance from the front edge of auxiliary table 1^a, 1^b, regardless of the width of said strip or the size of the caps produced. It is for this reason that plates 276 and 273^a are slotted 105 transversely to the line of travel of stock strip 15, so that the outermost point in the circumference of dies 272, 273 may be brought to the same point relatively to the forward edge of said strip whether larger 110 or smaller dies be used.

Die 273 is held in place by a cover-plate 279 having a central opening of slightly larger diameter than die 272 or the companion die 273. On top of retaining plate 279 115 are placed two stripper plates 280, 281 capable of adjustment toward and from each other, and each having a semicircular recess on its inner edge, said edges conforming 120 nearly to the outline of the opening in cover-plate 279 but protruding sufficiently to strip off from die 272 the stock strip 15 should it show any tendency to be carried up by said die on its upward movement. Stripper plates 280, 281 are adjustable in a direction 125 toward and from upright panel 3 of the main frame so as to bring them not only into proper distance one from the other, but also to make the opening formed by their semi-circular edge portions, concentric with the 130

die members. They are clamped in adjusted position by screws, as shown in Fig. 31.

Immediately below the top level of supporting block 274 there is attached to the inner or rear side of its inner vertical wall, an inclined plate or guide 282 onto which the punched disk or cap 283 falls as indicated in Fig. 30, causing the forward or outside edge of said cap to contact first with an endless carrier belt 284 extending beneath block 274 and running outward horizontally, to deliver the finished caps to the paraffining apparatus shown in Figs. 33 to 36. Belt 284 passes about a pulley 285 beneath block 274, to and around a roll 286 (see Fig. 33) carried by a shaft 287 mounted in bearings rising from a double-walled paraffin tank 288. This tank is mounted upon a suitable frame 289 and carries on its upper flanges a framework 290 in which are journaled the shaft 287 and shafts 291, 292 of felt-covered rolls 293, 294. Shaft 291 is journaled in fixed bearings, but the journals of shaft 292 are carried in blocks 295 slideable in frame 290, and urged toward the fixed bearings of shaft 291 by adjusting screws 296, springs being introduced between the sliding blocks and a fixed portion of frame 290, to support rolls 293, 294 when screws 296 are backed away.

Journaled in frame 289 is a power shaft 297 carrying a belt-wheel 298 through which it receives motion by belt from any prime motor or convenient source of power. Shaft 297 also carries at one end a sprocket-wheel 299 about which passes an endless chain 300 which imparts rotary motion to shaft 291 through a sprocket-wheel 301 carried by said shaft, which through the medium of a chain 302 passing about a sprocket-wheel 303 on shaft 287 imparts rotation thereto and to roll 286 thereon. The inner pot or vessel 304 of paraffin tank 288 is formed with a spout or conduit 305 of progressively increasing width from its upper to its lower end, the passageway through said spout being continued through the bottom of the outer pot or vessel, as shown in Fig. 36. This spout or conduit rises to the top of paraffin tank 288, the open upper end or mouth thereof extending directly beneath the nip of the rolls 293, 294 and being of a measurement slightly greater than the diameter of the largest cap or disk for which the machine is designed. Steam, hot water, or other heating medium is introduced into the space between the inner and outer vessels of tank 288 through an inlet pipe 306, to heat the paraffin which is contained in the inner vessel 304 and fills the same to a level slightly below the top of spout 305. The hot water or condensed steam escapes by an outlet pipe 307 opening from the bottom of the outer vessel of the tank.

The paraffining rolls 293, 294 are of a di-

ameter to dip into the paraffin in tank 288 to a depth sufficient to take up and become saturated by the paraffin in its molten state, and care should be taken to keep a sufficient quantity of paraffin in tank 288 to maintain such level. The delivery end of belt 284 stands just above the bite of rolls 293, 294, and the caps or disks 283 dropping off are guided by a plate or guard 308 into such bite or meeting point of said rolls which, owing to the yielding felt covering, grasp the cap or disk and draw it through them, dropping it directly into the open mouth of spout or conduit 305. Beneath spout or conduit 305 is an endless belt 309 carried about rolls 310, 311 journaled in frame 289, and driven as presently explained. Belt 309 carries forward the disks 283 and drops them over its delivery end through a guide spout 312, vertically into the threads or blades of two endless spirals or screw conveyors 313, 314, which are respectively threaded right and left and turn toward each other, being rotated by spiral gears 315, 316 meshing with like gears 317, 318 carried by a shaft 319 which receives motion by chain belt 320 from a sprocket-wheel 321 carried by power shaft 297, said chain passing also about a sprocket-wheel carried by shaft 319. Roll 311 about which passes carrier-belt 320 is rotated by a chain belt 322 passing about a sprocket-wheel 323 secured to shaft 324 of said roll 311, and also about a sprocket-wheel on driven shaft 319.

At the outer end of the double screw conveyor there is a mouth-piece 325 of the form shown in Fig. 37, said mouth-piece being supported by a frame or bar 326 extending out from the main frame 289 of the paraffining apparatus, said bar constituting a floor or support between the screw conveyors 313, 314 upon which the edges of the caps or seals rest as they are advanced toward the mouth-piece 325. This mouth-piece is of a diameter to receive a tube or carton 327 of card-board or pulp-board, of a diameter to freely receive the caps or seals. Preparatory to using the tube or carton 327 one end thereof is introduced into a crimping cup 328, the shaft of which is journaled in a bearing 329 projecting from framework 289. This cup 328 receives rotary motion through bevel pinions 330, 331 carried respectively by the shaft of the crimping cup and by driven shaft 319. The tube or carton, being pressed longitudinally into the rounding base or cup 328, is turned inward upon itself, producing an annular shoulder and reducing the diameter of the tube at that point by the thickness of the material of which it is made. The tube is then withdrawn from the crimping cup, reversed end for end, and the uncrimped end is introduced into the mouth-piece 325 at the delivery end of spiral conveyors 313, 314, and held in that position until it becomes

evident by a tendency of the tube to move outward, that finished caps or disks sufficient to fill the tube to the inturned shoulder have been delivered into it. The operator immediately withdraws the filled tube and introduces the uncrimped end of a second tube. He then inserts the uncrimped end of the filled tube into the crimping cup, and crimps it to prevent escape of the finished caps from that end of the tube.

It is desirable that the filled tubes be of uniform length, and to ensure this result and facilitate the final crimping, there is provided an upstanding lever 332, fulcrumed in a base block 333 and playing at its lower end between two arms 334, 335, the latter provided with an adjustable stop-screw 336 by which the swing of lever 332 toward the paraffining apparatus may be limited and determined. Pivotaly attached to lever 332 at the height of crimping cup 328, is a raised plate or cup 337 adapted to receive one end of the filled tube. The crimped end is introduced into this cup, and the uncrimped end into the crimping cup 328, and longitudinal pressure is applied by lever 332 to the tube, causing the end in the crimping cup to be crimped, such crimping proceeding until lever 332 is arrested by stop-screw 336. As this is a fixed stop after initial adjustment, it will be seen that the crimping will continue until the tube is brought to a predetermined length, and that the length of different tubes will be the same.

To support the tube while it is being filled by the screw conveyors 313, 314, a rod 338 is extended forward from mouth-piece 325, and provided with a crotch or yoke 339 into which the outer end of the tube may be laid, as shown in Fig. 33.

To guard against escape of the completed caps or disks from the belts 284 and 309, longitudinal guards 340 with inwardly turned flanges or edges to stiffen and better to guard the belts, are provided as best shown in Fig. 35. They are also seen in Fig. 33 and in top edge view in Fig. 34.

Numeral 341 (Fig. 29) designates a blade or cutter carried by block 269, which blade moving past the edge of base block 274, shears off the small fragments at the forward end of stock strip 15, and these fall into a suitable receptacle, preferably a pipe connected with an exhaust fan by which they are carried off to any suitable point.

What is claimed is:—

1. In a machine for producing bottle caps from a continuous stock strip, the combination of a main supporting frame; and a series of unit mechanisms, each designed and positioned to perform, in regular sequence, a definite operation or step upon the stock strip in the production of the caps, said unit mechanisms being independently and detachably secured to the supporting frame,

whereby each unit may be independently removed intact and re-installed or replaced by another.

2. In a machine for producing bottle caps from a continuous stock strip, the combination of a main supporting frame; and a series of unit mechanisms, each designed and positioned to perform, in regular sequence, a definite operation or step upon the stock strip in the production of the caps, 75 said unit mechanisms being independently and detachably secured to the supporting frame, at least one of said units being adjustable in the direction of movement of the stock strip and others of said units having 80 that portion which operates upon the stock strip adjustable in the direction of movement of said strip.

3. In a machine for producing bottle caps or seals from a continuous strip of stock, a series of unit mechanisms each complete in itself and each designed to perform one step or operation in the production of the finished caps, one of said units being a mechanism for feeding and stapling a separately formed tab, said unit being adjustable in the direction of travel of the stock strip, and others of said units having portions which operate upon the stock strip, said portions being adjustable in the direction of travel of the stock strip.

4. In a machine of the character described, the combination of a main supporting frame; and a series of independent unit mechanisms each designed and adapted to act upon a continuous stock strip and to perform thereon one or another of the several operations requisite to the production of a completed bottle cap or seal, certain of said mechanisms having parts adjustable to the requirements of caps of different sizes.

5. A bottle cap machine for producing caps of different sizes from a continuous stock strip, comprising a main frame; a scoring device for outlining by incisions in the stock strip, a recess or seat for a tab or pull-piece; and a milling wheel for removing material from the stock strip within the area so defined, said scoring and milling means being mounted in a common support, the scoring head or block being adjustable relatively to the milling wheel, whereby said parts may be caused to act upon one and the same cap-producing section of the stock strip whether the machine be adjusted to produce caps of a larger or of a smaller size.

6. In a machine of the character described, feeding mechanism for advancing a continuous strip or band of material, comprising two rolls between which the material is carried, and by which it is gripped; gearing connecting said rolls to cause them to turn with equal surface speeds; an axle for one of said rolls, occupying a fixed position; an 130

- axle for the other of said rolls having a supporting journal mounted to turn in a fixed bearing, the roll-carrying portion of the axle having its axis of rotation eccentric to that of the supporting journal; and means for turning the journal of said axle, whereby its roll is caused to approach or to recede from the companion roll, to grip or to release the interposed material.
- 10 7. In a machine for producing bottle caps from a continuous strip of material, a pair of feed rolls geared to rotate toward each other at like surface speeds; a cylindrical axle for one of said rolls carried in a fixed support; an axle for the other of said rolls, having a journal portion mounted in a fixed support, and a roll-bearing portion axially eccentric to the journal portion; means for turning the last-mentioned axle to cause one roll to approach or to recede from the other; a Geneva stop-wheel connected with one of said rolls; and an actuating roll for said stop-wheel carried by an arm revolvable about a fixed axis, whereby the rolls are intermittently operated and are caused to advance the interposed material a predetermined and uniform distance at each operation, when the rolls are adjusted to grip said material.
- 20 8. In a bottle cap machine designed to produce caps of two or more sizes from a continuous stock strip, a supporting frame; a driving mechanism; stock-feeding mechanism comprising a pair of rolls between which said stock strip is carried and by which it is gripped and advanced, gearing connecting said rolls to cause them to rotate at equal surface speed, a swinging support carrying the axle of one of said rolls, and means for clamping said support at desired adjustment; a lever carrying the axle of the other roll, whereby said second roll is rendered capable of movement toward and from the companion roll; a weight adjustable upon said lever to vary and determine the pressure of the rolls upon the material fed between them; Geneva stop mechanism serving to impart rotation to one of said rolls, the rolls being readily removable and replaceable by others of different diameter, whereby the feed may be varied for producing caps of two or more different sizes; driving connections from said driving mechanism to said Geneva stop mechanism; punching mechanism mounted in fixed relation to said frame in position to operate on the stock strip beyond said feed rolls; and a plurality of mechanisms supported on said frame, arranged to be driven by said driving means and to operate upon said stock strip between said feeding rolls and said punch, the point of action of said mechanisms upon the stock strip being adjustable in the direction of movement of said strip.
- 25 9. In a machine for making bottle caps from a continuous stock strip, a milling wheel for producing tab seats at regular intervals in said stock strip, said wheel mounted in a carriage movable transversely to the strip a distance sufficient to carry the milling wheel to and from its cutting position over the stock strip; means for feeding said stock strip step-by-step with intervening dwell periods; means for reciprocating said carriage, in such timed relation with the movement of the stock strip that the milling wheel engages said strip only during such dwell periods; and means for adjusting said milling wheel on its arbor, whereby its point of action on the stock strip may be varied.
- 30 10. In a machine for making bottle caps from a continuous stock strip, a milling wheel for removing stock from said strip to produce a seat for a tab or pull-piece; a reciprocating carriage in which said wheel is mounted; a supporting block in which the carriage is mounted to move to and from its cutting position; and means for adjusting said block with its carriage and milling wheel to adjust and determine the depth of the seat cut.
- 35 11. In a machine for making bottle caps, provided with staple-forming and driving mechanism for securing a tab or pull-piece to the cap, a wire feed comprising two feed rolls geared to rotate at equal surface speeds; axles for said rolls, journaled in bearings, one of said axles being set eccentrically to its journal; and means for rotating the last-mentioned axle to cause recession or approach of its roll from or toward the companion roll.
- 40 12. In a wire feed such as set forth in claim 11, a tensioning device for the wire, comprising a guide member through which the wire is carried, and a spring attached at one end to said guide member and at the other end to a fixed support.
- 45 13. In a machine for producing a bottle cap having a tab or pull-piece stapled thereto, staple-forming and driving mechanism comprising two slides, one straddling the other; means for moving said slides in proper relative timing toward and across the path of a stock wire; a supporting block for the incoming wire; means for periodically advancing the wire beyond the supporting block a staple length; an anvil block movable at right angles to the incoming wire, and having a ledge at the wire level to receive and support the wire; a wire-holding and staple driving plate carried by one of said slides; plates carried by the two arms of the other slide, one movable across the end of the wire-supporting block to shear off a staple length, and both movable past the anvil block and serving to bend down the leg-forming portions of the severed wire.

staple blank, the staple-driving slide having a beveled face to bear against and force back the anvil block as the staple is completed; and means to return the anvil block to wire-
5 supporting position.

14. In a machine for producing tabbed bottle caps, staple-forming and driving mechanism comprising a wire cutting and bending slide and a driving slide, each con-
10 sisting of a main and a secondary section, the secondary section movable relatively to the main section in the direction of the length of the latter; and a spring for moving the secondary section outward from the
15 main section, whereby the secondary section is enabled to stop on meeting undue resistance but the main section is enabled to continue its movement without causing breakage or injury of associated parts.

16. In a machine for producing tabbed bottle caps, the combination of a reel for a coiled tab strip; means for alternately advancing the tab strip a tab length and holding said strip against movement; a cutter for severing a tab length from said strip, said cutter including a bed or plate and a rolling knife connecting therewith; and means for actuating said cutter, timed to move the same across the tab strip and back into cutting relation with said plate during the periods of rest of the tab strip, whereby the cutter is caused to perform its function while the strip is at rest, and is held clear of the strip during its feeding movement.

17. In a machine for making tabbed bottle caps, feeding mechanism serving to advance a stock strip of tab material one tab length at a time across a supporting bed or plate; a cutting wheel for severing successive tab lengths from the stock strip; a swinging carrier for said cutter wheel; a supporting plate for the tab strip; and means for oscillating said carrier to move the cutting wheel across the stock strip and supporting plate, said carrier comprising a carrying block in which the cutter is mounted, movable relatively to and in the direction of the length of the carrier, whereby the cutting wheel is maintained in rolling contact with the supporting plate for said tab-stock strip notwithstanding the swinging movement of the carrier.

18. In a machine for producing printed bottle caps, the combination of a supporting bed or table over which a stock strip is fed; means for alternately advancing said strip a predetermined distance and holding it against movement; and printing mechanism comprising a vertically reciprocating slide carrying a printing form, endless carriers provided with inking-rolls for inking the form, movable beneath the printing form and transversely to the stock strip, an ink fountain having an ink-delivery roll in posi-

tion to impart ink to the rollers of the endless carriers, ink-distributing disks located beneath the lower stretches of the endless carriers in position to support the ink rollers carried thereby, means for rotating the 70 distributing disks, and means for alternately lowering the slide to carry the printing form into contact with the stock strip and raising said form above the endless carriers, the means for raising and lowering the slide and 75 the means for alternately advancing and holding the stock strip being relatively timed to bring the printing-form into contact with said stock strip while the latter is at rest, and to advance the stock strip 80 while the slide is in its elevated position.

19. In a machine for producing printed bottle caps, the combination of a supporting bed or table over which a stock strip is fed; means for alternately advancing said strip a predetermined distance and holding it against movement; and printing mechanism comprising a vertically reciprocating slide, a printing-form adjustable on said slide in the direction of movement of the stock strip, 85 endless carriers provided with inking-rolls for inking the form, movable beneath the printing-form and transversely to the stock strip; and means for alternately lowering the slide to carry the printing-form into 90 contact with the stock strip, and raising said form above the endless carriers, the means for raising and lowering the slide and the means for alternately advancing and holding the stock strip being relatively timed to 95 bring the printing-form into contact with said stock strip while the latter is at rest, and to advance the stock strip while the slide is in its elevated position.

20. In a machine for making bottle caps, 100 means for cutting the caps from a stock strip, said means comprising a reciprocating slide and means for reciprocating the same; a plate adjustably secured to the end of the said slide; a male die carried by said plate; an annular die facing the male die; and an adjustable supporting plate for said die, whereby the dies may be relatively alined and both may be brought into proper position relative to the forward edge of the 105 travelling stock strip whether said strip be wider or narrower, for production of larger or smaller caps.

21. In a machine for making bottle caps, 110 means for cutting the caps from a stock strip, said means comprising a reciprocating slide and means for reciprocating the same; a plate adjustably secured to the end of said slide; a male die carried by said plate; an annular die facing the male die; an adjustable supporting plate for said die, whereby the dies may be relatively alined and both may be brought into proper position relative to the forward edge of the travelling stock strip whether said strip be 115 120 125 130

wider or narrower, for production of larger or smaller caps; and stripper plates above the stock strip level, adjustable toward and from each other to bring them into proper 5 relation to the dies whether the latter be of larger or smaller size.

21. In a machine for producing tabbed bottle caps of different sizes, the combination of a supporting frame; a driving mechanism; a feed mechanism for a stock strip, said mechanism being arranged to feed said strip intermittently uniform distances with intervening dwell periods after each period 10 of motion; means for adjusting said feeding mechanism to cause it to feed different uniform distances corresponding to the size of cap to be produced; dies arranged to be 15

operated by said driving mechanism, for severing caps from the stock strip, said dies being located in a fixed position relatively to said frame; and mechanisms located in the order stated between said stock-feeding mechanism and the dies, and forming a tab seat and for affixing a tab in said seat, the first of said two mechanisms being adjustable as to its point of operation on the stock strip, and the second of said mechanisms being bodily adjustable on said frame to change its point of action on the stock strip. 20 25 30

In testimony whereof I have signed my name to this specification.

HARRY L. COMPTON.
